UNITED STATES PATENT OFFICE

2,489,852

ELECTRONIC TRIGGER PULSE GENERATOR

Nathaniel Bishop, Fairfield, Conn., assignor to
General Electric Company, a corporation of
New York

Application December 4, 1944, Serial No. 566,498

4 Claims. (Cl. 250—36)

1

This invention relates to means for triggering control circuits.

Where triggering devices, such as multivibrators, for example, are employed in applications where the device must be accurately triggered, it is desirable to have the trigger pulses of short duration, steep rise to maximum amplitude and constant frequency. Different circuits have been employed to provide steep pulses of short duration. However, the circuits heretofore used have required large units having a number of circuits in order to provide a reasonable degree of frequency stability.

It is an object of my invention to provide a new and improved circuit for providing equally spaced trigger pulses at a substantially constant frequency.

It is another object of my invention to provide a new and improved circuit which is simple in nature and employs a minimum number of circuit elements for providing equally spaced trigger pulses at a substantially constant frequency.

The features of my invention which I believe to be novel are set forth with particularity in the appended claims. My invention itself, both as to its organization and manner of operation, together with further objects and advantages thereof may best be understood by reference to the following description taken in connection with the accompanying drawing in which Fig. 1 is a schematic diagram of one embodiment of my invention; Fig. 2 discloses graphically some of the operating characteristics of the circuit shown in Fig. 1, and Figs. 3 and 4 show different embodiments of the principles of my invention.

Referring to Fig. 1 of the drawing, there is shown an oscillatory circuit 10 of the Hartley type including a tuned circuit comprising a tapped inductance 11 and a capacitor 12. Either or both of the tuned circuit elements may be variable if variable frequency of oscillations is desired.

The oscillatory circuit also includes an electron discharge device of the pentode type. The cathode 14 is connected to a suitable tap on the coil 11. The anode element 15 is connected to a suitable source of positive potential and is bypassed to ground through capacitor 17. The suppressor grid 18 is shown grounded although it may be tied to the cathode if preferred. The grid element 19 is connected to one side of the tuned circuit through grid leak 20 and grid condenser 21. The other side of the tuned circuit is grounded. It will be observed that the oscillatory circuit is the conventional Hartley circuit except that the screen grid element is not bypassed to ground.

2

The oscillatory circuit is biased for operation as a class C oscillator. Therefore, the electron discharge device is driven to saturation during each positive half cycle of the oscillatory wave and a substantially square pulse results on the screen grid and anode.

The substantially square waves are impressed upon a suitable frequency selective circuit, including a differentiation device, of such character as to discriminate against low frequency components such as the fundamental and lower order harmonics present in the voltage applied thereto. In Fig. 1, there is shown one form of a suitable frequency selective circuit. The screen grid control electrode or element 22 of the electron discharge device is connected to the upper end of a screen load impedance illustrated in the form of a resistance 23. The other end of the resistor 23 is connected to the source of positive voltage. The upper end of the resistor 23 is also connected to an R. C. differentiating circuit comprising a capacitor 24 and a resistor 25.

Referring to Fig. 2, there is shown at A the sine wave of voltage appearing on the grid element 19. At B in Fig. 2 there are illustrated the substantially square voltage waves appearing on screen element 22. The square waves have the same fundamental frequency as the sine wave voltage shown at A in Fig. 2. Typical negative and positive voltage pulses appearing at resistor 25 and applied to the utilization device or circuit 33, such as a pulser, are shown at C in Fig. 2.

It will be noted that in the circuit shown there is substantially no load on the oscillator so that the circuit is very stable and the pulses obtained therefrom are equally spaced apart, i. e., occur at a constant repetition rate. Either positive or negative pulses may be used for triggering depending upon the design of the triggering device. The oscillatory and differentiating circuits may be arranged to produce only positive or only negative pulses if desired.

Fig. 3 illustrates a second embodiment of my invention in which the substantially square pulses are taken from the anode element 15 of the electron discharge device, thereby providing pulses of a greater voltage swing. In this embodiment of my invention the screen grid element 22 is connected to a suitable source of positive potential through a suitable voltage dropping resistance 26 and is bypassed to ground through a capacitor 27. The anode element is connected to the source of positive potential through a suitable load impedance such as a resistor 23a. The source of positive potential is by-passed to ground

through a suitable capacitor 28. The substantially square pulses from anode 15 are impressed on the frequency selective circuit including resistor 23a in a manner similar to that shown in Fig. 1.

In Fig. 4 there is shown an adaptation of my invention to a crystal oscillator circuit. The grid circuit includes a suitable crystal 29 shunted by resistor 30. The plate circuit includes suitable inductance 31 and capacitor 32. The substantially square waves appearing across a suitable load impedance such as resistor 23b are impressed upon the differentiation circuit comprising capacitor 24 and resistance 25.

As indicated above, any network or device of suitable characteristics may be employed to differentiate pulses or voltage impressed thereon. For example, a small inductance shunted by a damping resistor or a transformer having low primary impedance could be used. The important thing is to arrange the frequency selective circuit to convert the substantially square pulses on screen grid electrode 22 or anode 15 to sharply peaked short duration pulses. Because of the stable nature of the lightly-loaded oscillator, these pulses will be equally spaced apart.

While I have shown and described a particular embodiment of my invention, it will be obvious to those skilled in the art that changes and modifications may be made without departing from my invention in its broader aspects, and I, therefore, aim in the appended claims to cover all such changes and modifications as fall within the true spirit and scope of my invention.

What I claim as new and desire to secure by Letters Patent of the United States is:

1. The combination of an oscillatory circuit comprising an electron discharge device including an anode electrode, a control electrode, a cathode electrode, and a screen grid electrode, a source of anode operating potential connected in circuit between said anode and cathode electrodes, means for impressing a substantially sine-wave oscillatory voltage on said control electrode, said means comprising a circuit resonant at a predetermined frequency and having a terminal thereof connected to said control electrode, means to bias said control electrode negatively to such an extent that discharge current flows between said cathode electrode and one of said remaining electrodes in a series of pulses recurring at said frequency, and means for differentiating the resulting voltage variations appearing on one of the remaining said electrodes of said electron discharge device, thereby to produce a series of sharply-peaked pulses recurring accurately at said frequency.

2. The combination of an oscillatory circuit including an electron discharge device having a plurality of elements including an anode, a cathode, a control electrode, and a screen grid electrode, a source of anode operating potential connected in circuit between said anode and said cathode, means for impressing a substantially sine-wave oscillatory voltage on said control electrode, said means comprising a circuit resonant at a predetermined frequency and having a terminal thereof connected to said control electrode, means to bias said control electrode negatively to such an extent that discharge current flows between said cathode and said screen grid electrode in a series of pulses recurring at said frequency, and means for differentiating the re-

sulting voltage variations appearing on said screen grid electrode.

3. The combination of an oscillatory circuit comprising an electron discharge device including an anode electrode, a control electrode, a cathode electrode and a screen grid electrode, a source of anode operating potential connected in circuit between said anode and cathode electrodes, means for impressing a substantially sine-wave oscillatory voltage on said control electrode, said means comprising a circuit resonant at a predetermined frequency and having a terminal thereof connected to said control electrode, means to bias said control electrode negatively to such an extent that discharge current flows between said cathode electrode and one of said remaining electrodes in a series of pulses recurring at said frequency, a utilization circuit, and frequency selective means connected between one of the other of said electrodes and said utilization circuit, said frequency selective means being arranged to convert the substantially square waves appearing on said one electrode into sharply-peaked relatively-short-duration substantially-equally-spaced-apart pulses.

4. The combination of an oscillatory circuit comprising an electron discharge device including an anode electrode, a cathode, a control electrode, and a screen grid electrode, a source of anode operating potential connected in circuit between said anode electrode and said cathode, means for impressing a substantially sine-wave oscillatory voltage on said control electrode, said means comprising a circuit resonant at a predetermined frequency and having a terminal thereof connected to said control electrode, means to bias said control electrode negatively to such an extent that discharge current flows between said cathode and said screen grid electrode in a series of pulses recurring at said frequency, a utilization circuit, and frequency selective means connected between said screen grid electrode and said utilization circuit, said frequency selective means being arranged to discriminate against the low frequency components of the voltage appearing on said screen grid electrode whereby the substantially square pulses impressed on said frequency selective means are converted into sharply-peaked relative-short-duration, substantially-equally-spaced-apart pulses at the input to said utilization device.
